UNITED STATES PATENT OFFICE.

TITUS F. HUTZEL AND JOHN HEINZMANN, OF ANN ARBOR, MICHIGAN.

GIG-TREE.

SPECIFICATION forming part of Letters Patent No. 310,136, dated December 30, 1884.

Application filed June 10, 1884. (No model.)

To all whom it may concern:

Be it known that we, TITUS F. HUTZEL and JOHN HEINZMANN, of Ann Arbor, in the county of Washtenaw and State of Michigan, 5 have invented a new and useful Improvement in Gig-Trees, of which the following is a specification.

Figure 1 is a perspective. Fig. 2 is a perspective of the seat, bottom view. Fig. 3 is 10 a detached view of the back-strap loop. Fig. 4 is a vertical longitudinal section. Fig. 5 is a section on an enlarged scale, taken on the line *x x*, Fig. 1; and Fig. 6 is a section, on an enlarged scale, of the seat.

15 Our invention consists in certain improvements in the construction of a gig-tree, which will be fully pointed out in the claims.

A represents the saddle-tree, having on its top a groove, B, cut deeper than usual, and 20 having its sides *b* beveled. Near the front of the saddle-tree a threaded hole, H, is cut through the same at the center of groove B, and the rear half of this hole H is surrounded by a raised boss, P. Back of the hole H 25 a slot, *i*, is cut through the saddle-tree, running crosswise the groove B. At the rear end of the groove B is a raised stud, K, the object of which is to hold the back-strap loop.

D represents the back-strap loop, having at 30 its rear end a loop, G, to receive the back-strap, and having a slot, F, cut therethrough to fit over the stud K. The forward end of the back-strap loop G is made with a downward and forward extending tongue, *d E*, which 35 is of such a size that it can be passed through the slot *i*, so that when the back-strap loop D is in place, as shown in Fig. 4, the part *d* of the tongue will lie within the slot *i*, and the part *E* will lie on the under side of the saddle-tree. It is obvious that this construction 40 locks the back-strap loop firmly in the saddle-tree, so that it cannot be removed without raising the rear end until the part *E* of the tongue is nearly at right angles with the bottom of groove B.

45 S represents the seat, and *e* represents a hole bored through the seat to receive the screw-bolt V, by which the various parts are held together. Surrounding the hole *e* the bottom of the seat S is raised, and this raised part M is beveled from front to rear, so that

it is higher forward of the hole *e* than back thereof. At the rear end of the bottom part of the seat is a projection, N, which is slanted toward the front of the saddle-tree, and acts 55 as a hook by passing under the bottom of that part of the saddle-tree in which the groove B is cut. On each side of hook N is formed a shoulder, *n n*, and these shoulders rest on the back-strap loop D, the hook N passing down 60 through the rear part of the slot F, which is enlarged for this purpose, as shown in the drawings.

C represents the check-rein hook, which may be of any style, that has a hole through 65 the shank to receive the screw-bolt V, by which it is held in place.

Our invention is put together and operates as follows: The tongue *d E* of the back-strap loop D is passed through the slot *i*, and the 70 loop D is then laid down in the groove B, so that the stud K projects through the slot F. The check-rein hook is then placed in the groove B, and the beveled sides *b* of the groove permit the use of hooks of different styles 75 and makes, while the raised boss P projects through the hole in the hook and affords an additional lock for the hook. The seat S is now placed in position so that the raised part M bears on the shank of the hook C, and the 80 hook N passes through the slot F until the shoulders *n n* rest on the loop D, and the seat is supported at these two points M *n*, it being so made that it does not rest at all on the saddle-tree. The screw-bolt V is now inserted 85 through hole *e*, and screwed into the threaded hole H, and as this screw is between the two points on which the seat rests, the part M is brought firmly down on the shank of hook C, and the shoulders *n n* are brought firmly 90 down on the back-strap loop D, so that both the hook C and the loop D are held firmly in position, and cannot shake or become loose so long as the screw-bolt holds.

What we claim as our invention, and desire 95 to secure by Letters Patent, is—

1. In a gig-tree, the combination, with the saddle-tree A, having therein the groove B, with beveled sides *b*, of the tongue E, check-rein hook C, back-strap loop D, having there- 100 in the slot F, and seat S, having on its under side the raised beveled part M, and the hook

N, with shoulders n n , substantially as shown and described.

2. The combination of the saddle-tree A, having therein the slot i , and the back-strap 5 loop D, having the tongue E integral therewith and bent down below the general plane of the shank of said back-strap loop, and adapted to enter the slot i and bear against

the under side of the saddle-tree, whereby the back-strap loop is securely held in position, substantially as shown and described.

TITUS F. HUTZEL.
JOHN HEINZMANN.
